UNITED STATES PATENT OFFICE.

LONGLEY LEWIS SAGENDORPH, OF CINCINNATI, OHIO, ASSIGNOR OF ONE-HALF TO HARLAN P. LLOYD, OF SAME PLACE.

CLEAT FOR METALLIC ROOFING.

SPECIFICATION forming part of Letters Patent No. 390,806, dated October 9, 1888.

Application filed June 15, 1888. Serial No. 277,250. (No model.)

To all whom it may concern:

Be it known that I, LONGLEY LEWIS SAGENDORPH, a citizen of the United States, and a resident of Cincinnati, in the county of Hamilton and State of Ohio, have invented certain new and useful Improvements in Cleats for Metallic Roofing, of which the following is a specification.

The object of my invention is to provide a cleat for locking sheets of metallic roofing which shall act in the nature of an anchor for said roofing-sheets, as will hereinafter appear.

In the drawings accompanying this specification and forming a part thereof, Figure 1 is a perspective view of the preferable form of cleat as it comes from the die. Fig. 2 is a perspective view of the cleat shown in Fig. 1 when ready for use. Fig. 3 is a view of a sheet of metal roofing, partly broken away, showing the cleat in position thereon ready for the insertion of the adjoining sheet of roofing. Fig. 4 is a perspective view of two sheets of roofing, partly broken away, with the cleat in position thereon. Fig. 5 is a perspective view of one form of ridge-cap as preferably constructed for use in connection with the cleat. Fig. 6 is a vertical central cross-section taken through the cleat and ridge-cap. Fig. 7 is a vertical cross-section taken through the center of the cleat, ridge-cap, and roofing-sheets, showing their relative positions when to place.

The cleat is formed from a sheet of suitable metal, and is preferably stamped or cut therefrom in the configuration shown in Fig. 1, consisting of the following parts, viz: A base, A, is formed at rear of said cleat, said base having two forwardly-projecting tongues, *a a*. The center portion, B, of the cleat is formed between the tongues *a a* and D D, and when bent to proper position for use said center portion is at about right angles to the base-tongues *a a*. The overlapping flange C is formed integral with the center portion, B, said flange being the entire width of the cleat. From the rear of said flange C are two rearwardly-projecting tongues, D D, one at each side thereof, said tongues corresponding in width to the tongues *a a* of the base.

The die forming said cleat is so made that all the afore-described parts will be cut at one

stroke, the flange C being bent to position with the same stroke that cuts the cleat. The cleats are packed and shipped in the form shown in Fig. 1, the center portion being bent, 55 when desired, for use.

The afore-described cleat is applied to the roofing-sheets in the following manner: The sheet of roofing having been cut to proper length, its outer edge is securely fastened in 60 the usual manner, its inner edge being bent up, forming a flange, E. The cleat is now attached to this sheet of roofing by slipping the tongues D D over the top of the flange E, the base A of the cleat being under this sheet, as 65 shown. If desired, the projecting tongues *a a* may be nailed to the sheeting; but it is not absolutely necessary that said tongues be nailed at all, as will more fully appear. The tongues D D, overlapping the flange E of the roofing- 70 sheet, serve to anchor said sheet. The first sheet of roofing now being in position and the cleat secured thereto, the flange of the adjoining sheet is now slipped in under flange C of the cleat, as shown in Fig. 4, this latter sheet 75 resting on the tongues *a a*. (Shown in Fig. 3.) The cleat now being in position with reference to the roofing-sheets, the ridge-cap F is now placed in position over the cleat and seam, and the cap, cleat, and roofing-flanges are 80 pinched together with suitable tongs, the whole forming a complete dirt and water proof joint. When in position, the flange C of the cleat rests between the outward and inwardly curved flanges, *f*, of the ridge-cap F, as shown 85 in Fig. 6, and in this manner the ridge-cap is securely anchored to the roof.

It will be seen that by the above construction the entire roof is anchored in such a manner that no part of it can become loose and 90 blow away without taking the whole of the roof. The difficulty heretofore has been that the expansion and contraction of the metal roof had the tendency to loosen the cleats, and consequently the roofing-sheets. By the use 95 of my improved cleat this objection is removed, as ample opportunity is afforded for expansion and contraction.

The advantages of my improved cleat are apparent, and have been partially set forth. 100 It is simple in construction and cheap of manufacture. The facility for packing and ship-

ping is a very great advantage, as a large number of them may be stored in a small compass.

While it is preferred to use the form of ridge-cap shown in connection with my improved 5 cleat, the cleat may be used independently of the cap by bending the flange C down over the flanges of roofing and then covering the seam with an ordinary cap.

What I claim as new, and desire to secure 10 by Letters Patent, is—

1. A cleat for metal roofing-sheets, consisting of a base, A, having tongue projections *a*, center portion, B, and flange C, having the tongue projections D D, the whole being 15 stamped in one piece of metal, substantially as set forth.

2. In combination with two sheets of metal roofing having flanges E, a cleat constructed

substantially as described, the one sheet resting upon the base A, the tongues D D, overlapping the flange E of said sheet, and the adjoining sheet of roofing resting upon tongues *a a*, and having the flange C overlapping the flange of said last-named sheet, the whole being covered with a suitable ridge-cap, substantially as described. 20 25

3. In combination with a roofing-cleat having a central portion, B, tongues D D, and flange C, a ridge-cap, F, having an outwardly and inwardly curved flange, *f*, the flange C of the cleat resting between said flanges of the ridge-cap, substantially as set forth. 30
